(57) **CLAIM**

The ornamental design for a trash can as shown and described.

DESCRIPTION

FIG. 1 is a top front left perspective view of the trash can of the present invention;

FIG. 2 is a top rear right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a top front left perspective view thereof illustrating a first set of lids in an open position;

FIG. 9 is a rear right perspective view thereof illustrating the first set of lids in the open position; and,

FIG. 10 is a top front left perspective view thereof illustrating the first set of lids in an open position and a first set of bag retention rings in an open position.

The broken lines in the figures show portions of the trash can which form no part of the claimed design.

1 Claim, 9 Drawing Sheets
